UNITED STATES PATENT OFFICE.

ORVILLE U. DESHA, OF FORT COLLINS, COLORADO.

DESIGN FOR A FRAME FOR SPECTACLES.

59,339.

Specification for Design.

Patented Oct. 11, 1921.

Application filed April 26, 1918. Serial No. 231,039. Term of patent 14 years.

To all whom it may concern:

Be it known that I, ORVILLE U. DESHA, a citizen of the United States, residing at Fort Collins, in the county of Larimer and State of Colorado, have invented a new, original, and ornamental Design for a Frame for Spectacles, of which the following is a specification, reference being had to

the accompanying drawing, forming part thereof.

The figure is a plan view of a frame for spectacles, showing my new design.

I claim:

The original design for a frame for spectacles, as shown.

ORVILLE U. DESHA.
